UNITED STATES PATENT OFFICE.

WILLIAM KIRK, OF SOLOMON, KANSAS.

DOOR LATCH.

Application filed December 21, 1925. Serial No. 76,719.

This invention relates to resilient latches or locks and has for one of its objects to provide a latch construction for hinged or swinging doors or closures based on the principle or mode of operation of my sliding door latch patented on June 2, 1925, No. 1,540,134, in which the latch and resilient member are combined in one element.

Another object is to produce a sliding door latch forming an improvement over the latch disclosed in my said patent, the improvement consisting in the disclosure of means whereby the operating latch bar may be projected through the inner face of the door for operation of the latch as distinguished from a separate operating means attached to the latch bar.

A still further object is to produce a double latch which may be employed to latch a gate, door or the like at the top and bottom thereof, this construction being especially desirable on hog and sheep proof fence gates and the like.

With the general objects named in view, the invention consists of certain novel and useful features of construction and organization of parts as hereinafter described and claimed; and in order that it may be fully understood, reference is to be had to the accompanying drawings, in which:

Figure 1 is a broken face view of the exterior side of a swinging door and latch embodying the invention.

Figure 2 is a section on the line II—II of Figure 1.

Figure 3 is a face view of the interior side of the door and latch as shown in Figure 1.

Figure 4 is a section on the line IV—IV of Figure 1.

Figure 5 is a view of the top and bottom latch construction taken through a gate and illustrates the latch and keeper in face view.

Figure 6 is a section on the line VI—VI of Figure 5.

Figure 7 is a broken face view of the exterior side of a sliding door and improved latch embodying the invention.

Figure 8 is a section on the line VIII—VIII of Figure 7.

Figure 9 is a section on the line IX—IX of Figure 7.

Figure 10 is a face view of the interior side of the door and latch as shown in Figure 7.

In the said drawings, where like refer-

ence characters identify corresponding parts in all of the figures, and in order to correlate the similar parts of the two types of latches, one for swinging closures and the other for sliding closures, 1 indicates a latch bar which is bent so that one end 2 overlaps and lies parallel to an intermediate part of the bar 3, said parts being securely held fixed in this position by means of a bearing plate securely fastened to the closure. The intermediate portion 3 of the bar may be of any desired length (see Figure 5) and at the desired point turns at right angles and projects through a slot or opening 7 in the closure to form an operating handle for the operation of the latch bar. The latch bar 3 is, of course, formed of suitable material and due to the fact that two portions of its length are secured as described for rotation on their axes eccentrically of each other, force rotating the parts in the bearing plate is counteracted or resisted by the resiliency of the metal under the twisting stress thus applied. Secured to the frame 8 of the closure is a keeper 9 fastened in position by bolts or screws 10. The parts of the devices having thus been correlated to show the exact similarity of operation, applicant will now proceed to describe in detail the specific parts of the different types of latch.

Referring particularly to Figures 1 to 4 inclusive, 11 indicates a swinging closure hinged at 12 to swing into a door opening 9 or frame 8 to which is secured a keeper 9 formed at its end with a hook portion 13. The latch of this type has one end 2 abutting an intermediate portion 3 secured against the inner face of the closure 11 by means of a bearing plate, comprising a flat strap portion 14 held by bolts 15 and a loop portion 16 receiving the latch. The free end of the latch bar forms a continuation of the portion 3 thereof and passes through a suitable slot 7 in the closure 11 and then may extend upwardly or downwardly parallel to the door to form an operating handle 17.

To provide convenient means for locking the closure from the outside and also to guard the operating handle 17 from catching on swinging harness, straps, etc., the securing bolts 15 also secure to the outside face of the closure a metal plate 18 having a portion of one of its ends bent to loop shape as at 19 and slotted as at 20. A passageway 21 is thus provided for engagement

by the hasp of a padlock or the like for locking the closure from the outside, as said hasp when in engaged position prevents the operation of the handle in the direction indicated by the arrow, Figure 2. The other portion of said end of the strap 18, being in width preferably equal to the length of the handle, is bent at right angles to the closure as at 22 and thus forms a guard for the operating handle and also provides a convenient abutment for the thumb or finger when operating the latch as will be readily understood. In order to form a guard at the other side of the handle, a pair of suitable wedge-shaped members 23 project from the plate or strap 18. When the closure is swung entirely open, the handle 17 snaps over and engages a catch 24 to hold it in open position.

20 The bolts 15 at the inside of the closure clamp the ends of a handle 25 in position. The handle 25 projects a distance substantially equal to the length of the interior portion of the catch bar to form a guard, 25 and has its straight portion 26 spaced a slight distance from the latch bar, said straight portion being preferably formed with a slight bowed portion 27 for convenient engagement with a locking pin 28 (see 30 Figure 3), whereby the latch may be locked from inside against unauthorized opening of the closure. It will be evident that the latch is operated from inside the door by the operator grasping the handle 25 and 35 then applying his thumb or finger to the latch to pull it from engagement with the keeper 9. In order to prevent the latch from swinging too far and interfering with the proper entry of the closure in the frame, 40 the plate 14 below the hook or confining portion 16, is formed with a projecting stop flange 30.

In the structure as indicated in Figures 5 and 6, the ends of the latch bar 1 are each 45 bent to form end portions 2 and intermediate portions 3, said portions being each secured adjacent the top and bottom of the gate, door, or other closure, and at any convenient point the intermediate portion 3a projects through a slot 7 in the gate 31. Each looped portion is provided with a bearing plate 4, and a series of securing plates 32 on the inner face of the gate are employed to form bearings for the relatively 50 long bar. The gate frame 33 is provided adjacent its top and bottom with keepers 9 similar in all respects to the keeper 9 shown in Figures 1 to 4 inclusive.

60 The latch shown in Figures 7 to 10 inclusive, is substantially similar to the latch shown in my prior patent referred to above, except that the free end 17 of the plate, but is 65 terminated within the bearing plate, and projects turned at right angles as at 35. The sliding through a slot or opening 7 in the

door 36, it being noted in this connection that an inner bearing plate 37 is provided between the eccentrically pivoted portions of the latch bar and the door, although said plate is not necessary to the proper operation of the latch. The keeper 9 secured to the door frame 8 comprises an outwardly inclined portion 39 which is formed with a locking stud or projection 40 for engagement with the latch bar (see Figures 2 and 75 3). In order to assist the operator in operating the latch and sliding open the door, an auxiliary handle and guard 41 overlies the free looped end of the latch bar 42, and the operator merely grasps handles 41 and 42 80 and by squeezing together the parts operates the latch handle 42 in the direction indicated by the arrow Figure 2, to disengage its opposite end from the keeper. The door may then be slid away from the frame. 85

To provide convenient means for the sealing or locking of the door from the outside, as this type of door is admirably adapted for freight car use, the keeper 9 is formed near its top or bottom edge with a horizontal slot 43, whereby the curved end or a locking iron 44 may be interposed between the latch and the door to prevent disengagement of the former from the keeper. The end of the locking iron is provided with a slot 45 for engagement with a car seal, and the other end of the iron is securely fastened by a link 46 to an eye 47 carried by the keeper plate. If this type of door is desired for operation on a barn or the like, the locking 100 iron 44 and its parts will preferably be omitted, and the hasp or a padlock is engaged behind the latch as described to lock the latch in closed position.

To lock the latch from the inside the 105 horizontal portion 35 of the latch, where it projects through the slot 7 in the door, is formed with a bowed portion 49. In the device, as illustrated, a slotted stud or protuberance 50 formed on the inner bearing 110 plate 37 projects from the inside face of the door and is formed at its end with a recess to provide a passageway 51 between the handle 52 and the stud 44 within which any suitable type of locking pin may be inserted to prevent operation of the handle in the direction indicated by the arrow for the operation of the latch, it being understood, however, that any other type of recessed plate may be employed in place of the 115 projecting stud, if desired.

120 From the above description, it will be apparent that I have produced a device of the character described which possesses all of the features of advantage set forth as desirable, and while I have described and claimed the preferred embodiment of the same, I reserve the right to make all changes properly falling within the spirit and scope 125 of the appended claims.

I claim:

1. The combination with a closure, of a frame adapted to receive said closure, a keeper secured to said frame, a latch adapted to engage the keeper, said latch being formed of a continuous bar having a plurality of portions of its length adjacent and parallel, and a bearing plate securing said adjacent portions of the bar to the closure, a portion 10 of said bar projecting through the opening in the closure to form an operating handle.
2. The combination with a closure, of a frame adapted to receive said closure, a keeper secured to said frame, a latch adapted to engage the keeper, said latch being formed of a continuous bar having a plurality of portions of its length adjacent and parallel, a bearing plate securing said adjacent portions of the bar to the closure, a portion 15 of said bar projecting through the opening in the closure to form an operating handle, and means on the exterior of the door cooperating with the handle to prevent operation of the latch.
3. The combination with a closure, of a frame adapted to receive said closure, a keeper secured to said frame, a latch adapted to engage the keeper, said latch being formed of a continuous bar having a plurality of portions of its length adjacent and parallel, and a bearing plate securing said adjacent 20 portions of the bar to the closure with the latch extending at right angles to the closure, a portion of the bar projecting through the opening in the door to form an operating handle, and means on the exterior of the door cooperating with the handle to prevent operation of the latch.
4. The combination with a closure, of a frame adapted to receive said closure, a keeper secured to said frame, a latch adapted to engage the keeper, said latch being formed of a continuous bar having a plurality of portions of its length adjacent and parallel, a bearing plate securing said adjacent portions of the bar to the closure with the latch extending at right angles to the closure, a portion of the bar projecting through the opening in the door to form an operating handle, and means on the exterior of the door cooperating with the handle to prevent operation of the latch. 25
5. The combination with a closure, of a frame adapted to receive said closure, a keeper secured to said frame, a latch adapted to engage the keeper, said latch being formed of a continuous bar having a plurality of portions of its length adapted and parallel, a bearing plate securing said adjacent portions of the bar to the closure with the latch extending at right angles to the closure, a portion of the bar projecting through the opening in the door to form an operating handle, and means on the exterior of the door cooperating with the latch to prevent operation thereof. 30

In witness whereof I hereunto affix my signature.

WILLIAM KIRN.
